The ornamental design for a tool for mounting a wheel on a vehicle, as shown and described.

DESCRIPTION

FIG. 1 is a front perspective view of a tool for mounting a wheel on a vehicle showing my new design;

FIG. 2 is a top plan view thereof; the bottom is a mirror image of the top view;

FIG. 3 is a front elevation view thereof;

FIG. 4 is a rear elevation view thereof;

FIG. 5 is a left side elevation view thereof; and,

FIG. 6 is a right side elevation view thereof.
